H. BERNHARD,
BINDER CONSTRUCTION,
APPLICATION FILED NOV. 10, 1920.

1,384,507.

Patented July 12, 1921.

UNITED STATES PATENT OFFICE.

HIERONYMUS BERNHARD, OF ST. LOUIS, MISSOURI, ASSIGNOR TO GEORGE B. GANNETT, OF UNIVERSITY CITY, MISSOURI, AND ARCHIBALD B. LEWIS, OF ST. LOUIS, MISSOURI.

BINDER CONSTRUCTION.

1,384,507.

Specification of Letters Patent. Patented July 12, 1921.

Application filed November 10, 1920. Serial No. 423,168.

To all whom it may concern:

Be it known that I, HIERONYMUS BERNHARD, a citizen of the United States, and a resident of city of St. Louis, State of Missouri, have invented an Improvement in Binder Construction, of which the following is a specification.

This invention relates to binder construction, and with regard to certain more specific features, to a post construction for binding sheets into book form. The invention is also applicable to the binding of blocks of sheets detachably in covers.

Among the several objects of the invention may be noted the provision of a simple and improved post; the provision of an inexpensive and compact book or binder structure, and the provision of a durable and effective binder adapted to varying thicknesses and sizes of cover-members and varying thicknesses of sheets either in loose-leaf or pad form. Other objects will be in part obvious and in part pointed out hereinafter.

The invention accordingly comprises the features of construction and operation, combination of elements and arrangements of parts which are exemplified in the structure hereinafter described and the scope of the application of which will be indicated in the following claims.

In the accompanying drawings in which is shown one of various possible embodiments of the invention,

Figure 1 is an elevation of the assembled post;

Fig. 2 is a bottom view of Fig. 1;

Fig. 3 is an elevation of the elements of the post separated from one another;

Fig. 4 is a plan of a book, showing two posts therein; and

Fig. 5 is a sectional elevation on the line 5-5 of Fig. 4, showing the book closed.

Similar reference characters indicate corresponding parts throughout the several views of the drawings.

Referring now more particularly to Figs. 1, 2 and 3, there is illustrated at 1 a post, comprising a cylindrical member 3 internally threaded to receive a screw 5 the threaded end of which projects beyond the end of the cylindrical member, and receives a knurled nut or cap 7.

As shown in Fig. 3, the cylindrical mem-

ber is provided at one end with a recess 9 to receive a shoulder 11 on the nut 7. The shoulder gives a greater length of nut in contact with the screw without undue increase of the total length of the post.

When used in a book such as that illustrated at 13 in Figs. 4 and 5, the screw 5 is inserted through an aperture 15 in the back cover or cover-member 17 of the book, the head of the screw being located on the outer side of the cover, which may be countersunk if desired, and the shank of the screw projecting inwardly into the book, that is, upwardly when the book is opened on a horizontal surface and is thus in the position indicated in Fig. 4.

The cylindrical member 3 is then screwed onto the shank of the screw and is fixed tightly thereon, thus holding the cylindrical member and screw tightly against the inner and outer faces respectively of the back cover 17.

The paper 19, which may be in loose sheets or in pad form, is then inserted in the book by slipping it over the cylindrical member of the post, the paper being apertured as at 21 for this purpose. When the paper is in place on the cylindrical member the nut is screwed down upon the screw until the lower face of the nut abuts against the end face of the cylindrical member.

A book preferably has two of these post constructions and in some instances more than two. A two-post book is illustrated in Fig. 4.

The front cover 23 of the book need not be perforated or otherwise designed particularly for this post construction, and the only operation needed in preparing the back cover for this construction is simply the punching of the desired number of apertures 15. This means that the cover construction is unusually simple, and means moreover that the completed cover, ready for shipment, may be perfectly flat, as distinguished from the many constructions wherein the post is permanently secured to the cover during the manufacture of the latter and thus prevents the cover from being shipped as an entirely flat unit.

When paper is to be removed from the book it is necessary simply to unscrew the nut 7 from each post, remove the paper,

insert any new paper, and thread each nut 7 again on its post. In this operation the screw and cylindrical member are in nowise disturbed.

5 The several operations of assembling the post, applying paper, and removing paper, may ordinarily be done with the fingers without the use of tools. If stronger pressure is desired in securing the cylindrical 10 member to the screw, a screw-driver may be applied to the latter. As noted above, it is not necessary to take these two elements apart in removing or inserting paper in the book.

15 The construction of the present invention is automatically adapted to varying thicknesses of back cover-member, because it is not essential that the screw come exactly flush with the upper surface of the cap 7. 20 And minor departures from an exact flush relation does not affect the tightness with which the sheets are held, as such tightness is determined by the height of the cylindrical member 3. The post is useful with 25 varying thicknesses and sizes of sheets, because the aggregate thickness of the sheets may equal the height of the cylindrical member 3, or may be less than such height, as in either case the papers are held in the 30 book with equal security. The device is inexpensive to manufacture, readily applied to the book by comparatively unskilled labor, after shipment, and is not liable to derangement through the rough handling that 35 books of this type frequently receive in service.

From the above, it will be seen that the several objects of the invention are realized, and other advantageous results attained.

40 As various possible embodiments might be made of the above invention and as various changes might be made in the embodiment above set forth, it is to be understood that all matter herein set forth or shown in 45 the accompanying drawings is to be interpreted as illustrative and not in a limiting sense.

I claim:

1. In apparatus of the class described, in combination, a screw, a cylindrical member 50 adapted to coöperate with said screw, and a nut or cap adapted to coöperate with said screw and having a shoulder engaging in a recess in the cylindrical member.

2. In apparatus of the class described, in 55 combination, a screw, a cylindrical member internally threaded and adapted to coöperate with said screw, and a knurled nut or cap internally threaded to coöperate with said screw and having a shoulder engaging 60 in a recess in the cylindrical member.

3. In apparatus of the class described, in combination, a screw adapted to pass through a perforation in the back cover of a book, a cylindrical member internally 65 threaded to receive said screw and to co-operate with said screw so that said parts hold one another in position on said back cover and a knurled nut or cap internally threaded to receive said screw and hold said 70 paper in place, said nut having a shoulder engaging a recess in the cylindrical member.

4. In apparatus of the class described, in combination, a book having a front and back cover flexibly united, a plurality of perforations in the back cover adjacent the binding edge of the book, a plurality of posts in said perforations, each post comprising a screw passing through one of said perforations and into the book, a cylindrical 80 member threaded on said screw, the screw and member holding one another in position on the back cover, sheets of paper in said book, having perforations through which said cylindrical members pass, and a knurled 85 nut or cap threaded on each screw and abutting against the free end of the cylindrical member thereon and adapted to hold said paper in place in the book, said nut having a shoulder fitting in a recess in said member. 90

In testimony whereof I have signed my name to this specification this eighth day of November, 1920.

HIERONYMUS BERNHARD.
